UNITED STATES PATENT OFFICE

HUGO MAASHOFF AND GEORGE W. PRATT, OF NEW HAVEN, CONNECTICUT, ASSIGNEES
TO THE GREIST MANUFACTURING COMPANY, A CORPORATION OF CONNECTICUT

SEWING MACHINE RUFFLER

Application filed May 7, 1928. Serial No. 275,714.

This invention relates to that class of sewing machine rufflers generally known as "five-stitch" rufflers, in that they have heretofore usually been constructed to make a ruffle at each stitch of the sewing machine, or at each five, or a greater or lesser number of stitches; and the invention has for its object to provide a ruffler of the class referred to in which the adjustment from one class of work to the other may be readily and easily effected. To this end the invention comprises two ratchet wheels by which the intervals of the strokes of the ruffling blade may be controlled, both of said ratchet wheels, which are mounted on the same pivot pin, being constructed with a plurality of deep and shallow notches and one of said ratchet wheels being adjustable relative to the other on said pivot pin. In one position occupied by the adjustable ratchet wheel two deep notches on both of said wheels will be in register with each other, so that a ruffling stroke will be imparted to the ruffling blade at each five or six stitches of the machine, according to the number of shallow notches between the deep notches of one of said wheels; while in another position occupied by the adjustable ratchet wheel only a single deep notch of the adjustable wheel will be in register with a deep notch of the other wheel, so that a stroke of the ruffling blade will occur only at each ten or twelve or any other desired number of stitches of the sewing machine. The improved ruffler is also so constructed that, by proper adjustment, a ruffling stroke will be imparted to the ruffling blade at each stitch of the sewing machine; or the ruffling blade may be thrown out of action entirely when plain sewing is to be done.

In the accompanying drawings Figs. 1 and 2 are opposite side views of the improved ruffler. Figs. 3 and 4 are views similar to Fig. 2 but with certain parts in different positions of adjustment. Fig. 5 is a rear end view of the improved ruffler. Figs. 6, 7 and 8 are detail views of the ratchet wheels, Fig. 8 showing a modified form of one of the ratchet wheels.

Referring to the drawings, 12 denotes the frame of the ruffler provided, as usual, with a

forked forward end 13, to adapt the same for attachment to the presser bar of a sewing machine. Mounted on the frame 12, by a pin or rivet 14, is the main operating lever 15 forked at its forward end for engagement with a pin or screw carried by the needle bar of the sewing machine, and fulcrumed on the pin or rivet 14 is a pendulous lever 16 jointed at its lower end to the ruffling blade carrier 17 to which latter is attached the ruffling blade 17^a. The pendulous lever 16 is provided with an arm 16^a positioned beneath a contact screw 18 carried by the operating lever 15, said screw being frictionally retained in any desired position of adjustment by the spring 19 mounted on said operating lever 15.

Attached to a plate 20, pivotally secured to the frame 12 by a fulcrum pin or rivet 21, is a pivot pin or rivet 22 on which are mounted two ratchet wheels 23 and 24, adjacent or contiguous to each other. The outer ratchet wheel 23 is provided with three deep notches 23^a and 23^b, and with a plurality of shallow notches 23^c. The ratchet wheel 24 is provided with two deep notches 24^a and with a plurality of shallow notches 24^b between each of said deep notches. In the construction shown there are five of these shallow notches between said deep notches, thus providing for a stroke of the ruffling blade at each six stitches of the sewing machine, although it will be understood that said ratchet wheel might be constructed with a greater or lesser number of these shallow notches between each of the deep notches 24^a.

The ratchet wheels 23 and 24 are held in frictional engagement with each other so that they may rotate together. The ratchet wheel 23 is provided with an arcuate slot 23^d, and the ratchet wheel 24 is provided with a pin 24^c fitting in said slot. The ratchet wheel 23 is also provided with an outwardly extending pin 23^e by means of which the said ratchet wheel may be circularly adjusted relative to the ratchet wheel 24 to an extent permitted by the pin 24^c fitting in the slot 23^d of the ratchet wheel 23.

Attached to the plate 20 on which the ratchet wheels are mounted is a spring 25 having a tooth 25^a over which the teeth of

the ratchet wheel 24 ride, said tooth serving as a detent pawl for preventing backward rotation of the ratchet wheels.

The pendulous lever 16 is provided with a shoulder 16^b adapted to be engaged by a laterally extending pawl 26 integral with a spring-pressed pawl carrier 27 mounted on the main operating lever 15 and arranged to engage the teeth of the ratchet wheels 23 and 24 and also properly positioned to engage the said shoulder 16^b on the pendulous lever 16 when desired.

When the ratchet wheel 23 is in the position of adjustment shown in Fig. 2, the deep notches 23^a of said ratchet wheel will be in register with the two deep notches 24^a of the ratchet wheel 24; and thus, with the ratchet wheels constructed as herein shown, the said pawl 26 will fall into said deep notches 23^a and 24^a, so as to engage the said shoulder 16^b on the pendulous lever 16, at each six stitches of the sewing machine, so as to operate the said pendulous lever and impart a forward movement to the ruffling blade carrier and the ruffling blade affixed thereto, the said pawl being held out of engagement with the said shoulder 16^b when riding over the shallow notches of the ratchet wheels. When, however, the ratchet wheel 23 is in the position of adjustment shown in Fig. 3 the deep notch 23^b in said ratchet wheel will be in register with one of the deep notches 24^a of the ratchet wheel 24, while the other deep notch 24^a of the ratchet wheel 24 will be covered by the ratchet wheel 23, and thus the pawl 26 will, in the rotation of the said ratchet wheels, fall into the said registering deep notches 23^b and 24^a to impart a forward stroke to the ruffling blade, at each twelve stitches; said pawl being held out of said engagement with the said shoulder 16^b during the formation of eleven stitches.

When a ruffle is to be made at each stitch of the sewing machine the ratchet wheels may be lowered to the position shown in Fig. 4, as provided for in the construction shown by U. S. Patent No. 1,044,645, so that said ratchet wheels will be below the path of travel of the pawl 25, and the said pawl will therefore be in constant position to engage the shoulder 16^b on the pendulous lever 16, to impart a forward stroke to the ruffling blade at each stitch.

To render the ruffling blade inoperative, when plain sewing is to be done, the pawl carrier 27 may be adjusted to the position shown in Fig. 4 so as to be rendered inoperative, the said pawl being held in this inoperative position by the finger 19^a on the spring 19, said finger at such times engaging a recess 27^a in said pawl carrier.

The ruffler is provided with the usual separator plate 28 affixed to a carrier 29 which is removably attached to the frame 12 in a well-known manner.

Mounted on the contact finger 16^a of the pendulous lever is a contact lever 30 having a projection 30^a which may be adjusted to the position shown in dotted lines in Fig. 1 above the top of said finger so as to lessen the lost motion between the contact screw and said finger when unusually long strokes are to be imparted to the ruffling blade, this adjustable lever 30 being like that shown in U. S. application serial No. 264,846, filed March 26, 1928.

This contact lever is preferably employed to secure a very long throw of the ruffling blade in making wide pleats, and is considered preferable to the use of a long contact screw 18, by which the same result might be effected, as the adjustable lever can be thrown into or out of operation quickly, thus making the adjustment easier than by a long screw adjustment.

It is not essential that both of the ratchet wheels 23 and 24 should be constructed with shallow notches in addition to the deep notches, as one of said wheels, for example the outer wheel 23^c, might have a plain periphery between the deep notches, as shown in Fig. 8. This form of the said wheel may be of spring steel and will preferably be provided with two pins 23^e for convenient adjustment on the wheel 24, and may be frictionally retained in either position to which it may be adjusted by a depression 24^d which may engage properly spaced recesses in the outer face of the wheel 24.

From the foregoing it will be understood that the invention provides simple means whereby a ruffler is adapted to make a ruffling stroke at each stitch of a sewing machine, or between any desired number of a plurality of stitches, or may be thrown out of operation altogether when plain sewing is to be done.

Having thus described our invention, we claim and desire to secure by Letters Patent:—

1. In a sewing machine ruffler, the combination with a ruffling blade and means for reciprocating the same, of two ratchet wheels adapted to rotate together and each constructed with a plurality of deep notches, spaced apart from each other by intervening shallow notches, one of said wheels being circularly adjustable relative to the other.

2. In a sewing machine ruffler, the combination with a ruffling blade, and means for reciprocating the same, of two ratchet wheels, one of said wheels having two deep notches and a plurality of shallow notches, and the other of said wheels having three deep notches, one of said wheels being circularly adjustable relative to the other, said deep notches being spaced apart by intervening shallow notches.

3. In a sewing machine ruffler, the combination with a ruffling blade and means for reciprocating the same, of two adjacent rat-

chet wheels adapted to rotate together and each constructed with a plurality of spaced-apart deep notches, one, at least, of said wheels having a plurality of shallow notches, one of said wheels having an arcuate slot and the other having a pin extending into said slot so that one of said wheels may be circularly adjustable relative to the other.

4. In a sewing machine ruffler, the combination with a ruffling blade, of two ratchet wheels each having a plurality of spaced-apart deep notches, one, at least, of said wheels having also a plurality of shallow notches, one of said wheels being circularly adjustable relative to the other, and means for operating said ruffling blade and for intermittently rotating said wheels.

5. In a sewing machine ruffler, the combination with a ruffling blade, of two ratchet wheels each having a plurality of spaced-apart deep notches and one, at least, of said wheels having also a plurality of shallow notches, one of said wheels having an arcuate slot and the other having a pin extending into said slot so that one of said wheels may be circularly adjustable relative to the other, and means for operating said ruffling blade and for intermittently rotating said wheels.

30 In testimony whereof we affix our signatures.

HUGO MAASHOFF.
GEO. W. PRATT.
